UNITED STATES PATENT OFFICE

OLOF F. EDQVIST, OF DENVER, COLORADO.

ROTARY GAS-ENGINE.

988,319.

Specification of Letters Patent. Patented Apr. 4, 1911.

Application filed November 15, 1910. Serial No. 592,450.

To all whom it may concern:

Be it known that I, OLOF F. EDQVIST, a subject of the King of Sweden, residing in the city and county of Denver and State of Colorado, have invented a new and useful Rotary Gas-Engine, of which the following is a specification.

This invention relates to improvements in rotary gas engines, and the objects of the invention are: First—to provide a cylinder which is rotatably mounted upon a stationary shaft and which is provided with radial partitions, rotatable pistons being mounted in the cylinder which are adapted to move therewith but at a greater rate of speed, means being provided for automatically and successively locking said pistons to the shaft at equidistant points in their rotation and for momentary periods, the locked piston standing adjacent to one of the said partitions and being adapted to form an abutment to receive the impact from an explosion of gas which has been previously compressed between said piston and abutment, whereby the cylinder is given a rotary impulse, means being provided for unlocking the pistons successively immediately following the explosions. Second—to provide a rotatable cylinder mounted upon a stationary shaft and provided with rotatable pistons having spring actuated dogs adapted to automatically lock said pistons in successive order to the shaft, each piston as it is locked being arranged to unlock the other piston, arms being pivotally secured to the cylinder and to the pistons, whereby the pistons are rotated intermittently and at a greater rate of speed than the cylinder, said pistons being adapted to act as momentary abutments to receive the impact of an explosion of gas, the cylinder having partition blocks which are adapted to be positioned adjacent to the locked pistons when the explosion occurs, whereby the cylinder is given rotary impulses in successive order, valves being provided for automatically admitting the explosive mixture to the cylinder, and for permitting the exploded gas to exhaust. These objects are accomplished by the mechanism illustrated in the accompanying drawings, in which:

Figure 1 is a side elevation of the improved engine. Fig. 2 is a side elevation of the opposite side of the engine. Fig. 3

is a vertical, sectional view through the engine cylinder at right angles to its axis. Fig. 4 is a vertical, sectional view of the engine taken on the line 4—4 of Fig. 1. Fig. 5 is a sectional view taken on the line 5—5 of Fig. 3. Fig. 6 is an elevation of the side of the engine shown in Fig. 1, but omitting the front supporting standard and parts carried thereby. Figs. 7, 8, 9 and 10 are respectively a side view, a rear view, a plan view and a bottom view of one of the pistons. Fig. 11 is a transverse, sectional view through a portion of the timer ring; and Fig. 12 is a view in diagram illustrating the spark circuit.

Referring to the accompanying drawings, the numeral 1 indicates a shaft which is rigidly mounted in standards 2. Centrally of its length, the shaft is provided with an annular enlargement or collar 3, which is provided centrally of its width with an annular groove 4. Substantially a third of the length of the shaft from each end is tubular or formed with an axial bore and these bores or passages 5 and 6 constitute respectively inlet and exhaust ports for the engine. At the inner ends of the bores apertures 7 and 8 respectively extend through the tubular portions of the shaft. The apertures 7 communicate with a surrounding hub 9, which is revolvably mounted on the axle, and from which extend short oppositely positioned pipes 10, to which are secured straight, horizontally arranged elbows 11, the opposite ends of which are adapted to be secured to one side of the engine cylinder, as will presently be shown. The adjoining ends of the pipes and elbows are preferably flanged, as shown, so as to be connected by bolts 12, and the ends of the elbows which connect with the cylinder are also flanged, as shown at 13. These pipes and elbows are adapted to convey explosive mixture to the cylinder, a suitable carburetor (not shown) being secured to the adjacent end of the shaft so as to connect with the port or passage 5. The elbows are provided with inlet valves, to be fully described hereinafter.

The apertures 8 at the inner end of the exhaust port 6 communicate with a surrounding hub 14, similar in all respects to the hub 9, and which is also revolvably mounted upon the shaft 1. From opposite points of this hub extend short pipes 15,

which are flanged at their ends, and to these flanged ends are connected straight horizontal elbows 16, which are also flanged at their ends adjoining the pipes, the adjoining pipe 5 and elbow flanges being secured together by bolts 17. The flanges 15 at the opposite ends of the elbows are adapted to be secured to the adjacent side of the cylinder, as will presently be shown, and these pipes and elbows with the shaft port 6 form an outlet for the exploded gases from the cylinder.

The cylinder comprises a band 19 of suitable width, to the opposite edges of which are secured plates or heads 20 by bolts 21, 15 which pass through holes in the band and heads. The heads 20 are provided with circular axial openings 21^A of greater diameter than the collar 3 on the shaft, and from diametrically opposite points partition blocks 20 22 extend from the margin of the openings 21^A to the band 19 and are secured by bolts 23, which pass through the said blocks and through the heads 20.

At right angles to the blocks 22 are oppositely arranged partition blocks 24 and 24^A, 25 which also extend from the margin of the openings 21^A to the band 19, and bolts 25 pass through these blocks and through the heads 20. The blocks 22 and 24 serve to brace the heads and to define the space between them and the bolts 25, prevent spreading of the heads due to the pressure resulting from the explosions in the cylinder, as will be apparent. The blocks 24 and 24^A 35 are provided at their inner ends with transverse grooves 26, which are adapted to receive packing strips 27, springs 28 being first placed in the grooves which exert an outward pressure upon the strips. The packing strips 27 are adapted to bear upon the segmental portions of rotary pistons A and B to be presently described.

The upper ends of the blocks 24 and 24^A are formed on one side with transverse, 45 semi-circular recesses 29, which are concentric with circular apertures 30 and 31 in the cylinder heads 20, and into these apertures 30 and 31 extend the shouldered ends of the elbows 11 and 16 respectively, the flanges 50 13 and 18 respectively of said elbows being bolted to the heads 20 by bolts 32.

The inner ends of the elbows 11 are formed with valve seats 33, in which are seated conical disk valves 34 having stems 35. The 55 ends of the elbows on a line with the valve seats are provided with threaded apertures, in which are screwed headed plugs 36 having axial holes extending partially through them, which form bearings for the ends of the valve stems 35. Near the inner ends of the elbows are located integral skeleton supports 37 having axial holes through which the stems 35 pass, and these supports or bearings offer no obstruction to the passage 60 of explosive mixture through the elbows.

Flanged collars 38 are secured upon the stems 35, and expansive coil springs 39 are interposed between the flanges of the said collars and the supports or bearings 37 and normally hold the valves 34 upon their seats. 70

The shouldered ends of the elbows 16, which extend into the holes 31, are provided with valve seats 40, upon which are seated conical disk valves 41 having stems 42, which extend out through axial holes in headed 75 plugs 43, which are screwed into the outer ends of the elbows, and upon the outer ends of these stems are secured heads 44. The heads of the plugs 43 are provided with countersunk recesses 45, which are adapted 80 to receive the inner ends of expansive coil springs 46, which are interposed between the said plugs and the heads 44 on the ends of the stems, and these springs serve to normally hold the valves 41 upon their seats. 85 Skeleton supports 47 are formed near the inner ends of the elbows 16 and are provided with axial holes, through which the valve stems 42 pass.

The pistons A and B, above mentioned, 90 comprise blades 48, which are radially disposed relatively to the axis of the cylinder, and from the inner ends of which extend segmental members 49. The blades are of a width to fit snugly between the cylinder 95 heads 20, and their outer ends are adapted to bear against the cylinder band 19. The lateral ends of the blades are provided with grooves 50, to receive packing strips 51 and springs 52, which are adapted to press the 100 said strips against the cylinder heads. The outer ends of the blades are also provided with grooves 53 to receive strips 54 and springs 55. The segmental portions 49 of the pistons are enough wider than the blades 105 to extend through the circular openings 21^A of the cylinder heads and lie flush with the outer faces of the said heads. The under sides of the said segmental portions 49 are formed with segmental recesses 56, of a 110 width and curvature corresponding to the shaft collar 3, and the portions of the member 49 on each side of the segmental recess 56 are formed with recesses 57 of a curvature corresponding to the curvature of the shaft. 115

In the centers of the recesses 56 are formed tongues 58, which are adapted to lie in the annular groove 4 of the collar 3, and these tongues are extended a suitable distance beyond that end of the member 49 farthest from the blade 48 and terminate in beveled ends 59, as shown. The blades 48 of the pistons are provided with slots or recesses 60, which extend into them from their inner ends. These slots are of a suitable depth and extend from one side of the segmental recess 56 to the other and centrally from the end walls of the slots holes 61 extend into the blades, and these holes serve as pockets 120 for coil springs 62. Latch blocks 63 are 125 65

placed in the slots 60 against the springs 62, and these blocks are slightly shorter than the depth of the slots 60 and are adapted to successively engage a plurality of stops 64 formed upon the shaft collar 3 on opposite sides of its annular groove 4, the stops being in the form of transverse grooves, as shown. When one of the pistons is brought to a momentary pause by the engagement 10 of its latch block 63 with a stop 64, the beveled end 59 of its tongue 58 passes under the latch block of the other piston and disengages the same from a stop, thereby permitting the latter piston to be moved relatively until its latch block is engaged by the next succeeding stop, its tongue at the same time effecting the release of the latch block of the former piston, as will be understood by reference to Fig. 3.

20 The manner of intermittently rotating the pistons and the object thereof is as follows: The segmental members of the pistons extend laterally through the openings 21^A of the piston heads, as before mentioned, and 25 one side of each of these members is formed with a radial groove or recess 65, the marginal edges of which are undercut, as shown in Figs. 9 and 10. A block 66 is placed in each of these grooves, and these blocks are 30 formed with beveled edges to correspond to the undercut edges of the said grooves. The blocks 66 are held in the grooves by screws 67, and from each block projects a stud 68, the outer ends of which are threaded. A 35 rod 69 extends transversely through the cylinder between a pair of the partitions 22 and 24^A, and upon one end of this rod is pivotally mounted an arm 70, to the free end of which are pivotally attached arms 40 71 and 72, the opposite ends of which are pivotally secured to the studs of the pistons A and B respectively, which are thereby given an intermittent rotary movement, as follows: Assuming that the piston A is 45 locked to the shaft by its latch block and that the cylinder is rotating in the direction of the arrow, as shown in Fig. 3, the arm 70, which moves with the cylinder, pushes the arm 71 and pulls the arm 72, as will be understood, and the arm 71 will swing up upon the stud of the said locked piston A, while the arm 72 will move the piston B, the latch of which was released by the beveled tongue of the piston A, from 50 the position shown in Fig. 3 to the next succeeding stop notch in the hub collar 3, and as it reaches this notch it is momentarily locked thereto by its latch block, while its tongue lifts the latch of the piston A, which 55 piston is instantly moved to the next succeeding stop notch. Thus, each piston, as it comes to a locked position unlocks the other piston and the movement of the pistons relatively to the cylinder is such that 60 65 when each one comes to a locked position

it has overtaken and stands adjoining one of the partition blocks 24 or 24^A, as the case may be, at which instant an explosion occurs between the said piston and block, and as the piston is momentarily locked the 70 power exerted against the block by the explosion gives a rotary impulse to the cylinder, by which the block is carried forward in advance of the piston, but as the outer ends of the arms 71 and 72 travel in an arc 75 of much greater radius than the studs of the pistons to which their inner ends are attached, and an arc that is also eccentric to the axis of the cylinder being defined by the swing of the arm that is attached to the 80 locked piston, the unlocked piston is therefore rotated at a greater rate of speed from one stop notch to another than the rate at which the cylinder is rotating. By reference to Fig. 3 it will be seen that the piston 85 A is locked to the shaft and stands adjoining the portion 24, and when the pistons and partitions are in these relative positions an explosion occurs, as will presently be explained, and as the partition is thrown forward in advance of the piston a vacuum is formed in the space between it and the piston, by which the inlet valve 34 is opened to admit a charge of explosive mixture, and almost simultaneously therewith, the opposite exhaust valve 41 is opened by the engagement of its valve stem head 44 with one of three cam projections 73 on a ring 74 that is secured to one of the supporting standards in any suitable manner, preferably by screws or bolts 74^A, which extend through the lower portion of the ring and legs of the standard, and through the upper end of the ring and a bracket 75 having a split collar member 76, which is clamped 105 upon the shaft by a bolt 77. The ring 74 is provided with three cams, as shown, and as there are but two diametrically opposite exhaust valves 41, it will be seen that these valves are opened in alternate order, as 110 when one valve stem head 44 is passing over a cam the opposite head is between two cams, as shown in Fig. 1.

The cylinder ring 19 is provided with diametrically opposite threaded apertures 115 78 and 79, which are located adjacent to the sides of the partitions 24 and 24^A, in which are formed the semi-circular recesses 29, and in these apertures 78 and 79 are screwed spark plugs 80 and 81 respectively to the insulated terminals of which are connected feed wires S2 and S3 respectively, while their other terminals are adapted to take the current through the cylinder, one of the supporting standards of which is connected by 120 a circuit wire S4 with a battery. The wires 82 and 83 are connected to bracket arms 85 and 86 respectively, which are connected at diametrically opposite points to one of 125 the cylinder heads, but are insulated there- 130

from by non-conducting elements 85^a and 86^a. The outer ends of these arms carry contact rollers 87 and 88 respectively, which are adapted to engage conductor rings or bands 89 and 90 respectively, which are separated by but secured upon a band 91 of any suitable non-conducting material, preferably fiber, so that an electric current passing through the outer ring 89 cannot be transmitted to the inner ring 90. Feed wires 92 and 93 respectively extend from these rings to one pole of a spark coil 94. The conductor rings 89 and 90 and non-conducting ring 91 are secured to the adjacent standard 2, and to the upper end of the bracket 75 by bolts or screws 94, which pass through the non-conducting ring 91 and through blocks 95 of non-conducting material which insulate the conducting rings 20 from the standard. These rings are concentric with the axis of the cylinder.

Within the inner ring 90 and concentric therewith is a timer comprising a non-conducting ring 96, in the periphery of which are spaced conductor rings 98 and 99, which are connected by wires 100 and 101 to the opposite pole of the spark coil 94, to which the wires 92 and 93 are connected. Connected with the ring 98 are three equidistant contacts 102, which are embedded in the ring so as to lie flush with its inner surface, and three similar contacts 103 are connected to the ring 99, the contacts 102 and 103 being arranged in pairs, as shown. The ring 96 is secured to the adjacent standard by screws or bolts 97. The inlet and exhaust hubs 9 and 14 are provided with stuffing boxes 9^a and 14^a respectively, which are closed by glands 9^b and 14^b respectively, and to the outer gland 14^b are secured arms 104 and 105 carrying contact rollers 106 and 107 respectively, which are positioned to travel over the contacts 102 and 103 respectively of the timer, and as the arms 104 and 105 are not insulated from the glands to which they are secured current from the timer passes through the rollers 106 and 107 to the said arms 104 and 105, and thence through the cylinder casing to the opposite poles of the spark plugs, from those to which the wires 82 and 83 are connected.

On the cylinder head opposite to the one to which the arms 85 and 86 are secured is bolted a driving pulley 108, and the inner face of this pulley is provided with gear teeth 109. A pinion 110 on a shaft 111, which is mounted in a bearing 112, meshes with the teeth 109, and the shaft 111 may be operated by a crank or in any other suitable way to start the engine.

The margin of each cylinder head opening 21^a is provided with annular grooves, in which are seated circular packing rings 113, which also extend into grooves 114 formed 65 in the segmental members of the pistons A

and B, and as the pistons rotate they slide upon these packing rings, as will be understood.

The operation of the machine is as follows: Assuming that the cylinder has been started by the manually operated wheel 116 and that the pistons are in the relative positions shown in Fig. 3, then the cylinder is in proper position for an explosion to take place between the piston and the adjacent partition block 24. At this instant the roller 106 engages one of the contacts 102, thereby forming an electric circuit through ring 98, wire 100, the spark coil 94, wire 92, conductor band 89, roller 87, arm 85 and wire 82 to one pole of the spark plug 80; thence through opposite pole of spark plug, the cylinder casing, arm 104 and roller 106, which completes the circuit. As this circuit is formed the explosion takes place and the cylinder is given a rotary impulse, by which the piston B, which was unlocked from the shaft simultaneously with the locking of the piston A, as previously described, is drawn upon by the arm 72 and at a greater rate of speed than that traveled by the cylinder, so that when it reaches the next succeeding step notch on the shaft hub and is locked thereto it has overtaken the partition 24^a and at the same instant the contact roller 97 passes over one of the contacts 103 in the timer ring and a circuit is formed through conductor ring 98, wire 101, spark coil 94, wire 93, conductor ring 99, roller 88, arm 86 and wire 83 to one pole of the spark plug 81; thence through the opposite pole and cylinder casing to arm 105 and roller 107, thus completing the circuit and thereby producing a spark at the plug 81 between piston B and the partition 24^a, by which the cylinder is given another rotary impulse. When the explosion occurred between the piston A and partition 24 the valve 34 was opened by the vacuum caused by the advancing piston to admit a charge of explosive mixture between the said piston and partition, and about the same time the valve 41 was opened in a manner before described to permit the exploded mixture to exhaust. The same results were accomplished when the explosion occurred between the piston B and the partition 24^a, and so on successively as each piston comes to a locked position to act as an abutment to receive the force of the explosion.

It will be noted that three explosions take place between each piston and its co-acting partition at every revolution of the cylinder, or six explosions in all. Thus, the cylinder is given six rotary impulses during every revolution.

Having described the invention, what I claim as new and desire to secure by Letters Patent is:

1. In a rotary gas engine, the combination

- tion with a stationary shaft, of a cylinder rotatably mounted thereon having oppositely arranged partitions, radially disposed pistons rotatably mounted on the shaft, 5 means for locking said pistons to the shaft at equidistant points in their relative travel and in alternate order, means for unlocking one piston simultaneously with the locking of the other piston, arms connected to the 10 cylinder and to the pistons for intermittently rotating the latter, and automatically operating inlet and exhaust valves which act at predetermined periods relatively to the locking of the pistons to the shaft.
- 15 2. In a rotary gas engine, the combination with a stationary shaft having equidistant stops arranged in radial order, of a cylinder rotatably mounted on the shaft having oppositely arranged partitions, radially disposed pistons rotatably mounted on said shaft, spring operated latches in said pistons for engaging said stops, means connected with the pistons whereby when one is locked the other is simultaneously 20 unlocked, arms pivotally connected to the cylinder and to the pistons for intermittently rotating the pistons, and oppositely arranged inlet and exhaust valves, which operate automatically at predetermined periods 25 relatively to the locking of the pistons to the shaft.
3. In a rotary gas engine, the combination with a stationary shaft having radially disposed stops thereon, of a cylinder rotatably mounted on said shaft having oppositely positioned partitions, oppositely arranged automatically operating inlet and exhaust valves adjacent to each partition, radially disposed pistons rotatably mounted 30 in said cylinder and adapted to act in conjunction with said partition in confining a volume of explosive mixture, latches in said pistons for engaging the said stops successively and in alternate order, means connected with the pistons whereby when one is locked to the shaft the other is simultaneously unlocked, and arms pivotally connected to the cylinder and to the pistons, whereby the latter are rotated intermittently.
4. In a rotary gas engine, the combination with a stationary shaft having radially disposed stops, of a cylinder rotatably mounted on said shaft having diametrically opposite partitions, radially disposed pistons in said 45 cylinder rotatably mounted on the shaft, spring operated latches in said pistons adapted to successively engage the said stops, an arm pivoted to the cylinder, and arms pivotally secured to the said arm and 50 to the pistons, whereby the pistons are rotated intermittently and at a greater rate of speed from one stop to the next succeeding stop than that traveled continuously by the cylinder, tongues on the pistons which act 55 alternately to unlock one piston simultane-
- ously with the locking of the other piston, and oppositely arranged inlet and exhaust valves adjacent to the said partitions.
5. In a rotary gas engine, a stationary shaft having radially disposed stops and 70 axial ports extending into its ends, which are intersected by radial ports, a cylinder rotatably mounted on the shaft having diametrically opposite partitions, hubs on the shaft surrounding the said radial ports, oppositely positioned pipes extending from each of said hubs, and straight horizontal elbows connected to said pipes and to the adjacent cylinder heads, which are apertured to receive the ends of the elbows, 75 spring controlled automatically operating valves in the elbows, those in one side of the cylinder being inlet valves and those on the opposite side being exhaust valves, rotatable, radial pistons on said shaft, arms connecting the pistons with the cylinder, latches in the pistons for successively engaging the said radial stops, and latch operating tongues on the pistons by which when one piston is locked its tongue unlocks the opposite piston, whereby the pistons are limited to intermittent movements in alternate order. 80
6. In a rotary gas engine, the combination of a stationary shaft having axial ports extending into its ends, which are intersected by radial ports, radially disposed stops on the shaft, a cylinder rotatably mounted on the shaft having diametrically opposite partitions, rotatable hubs surrounding the said radial ports, diametrically opposite pipes connecting each hub with the interior of the cylinder adjacent to the said partitions, automatically operating inlet valves in the pipes on one side of the cylinder and automatically operating exhaust, 90 valves in the pipes on the opposite side of the cylinder, pistons rotatably mounted on the shaft, latches carried by the pistons which engage the said stops successively and in alternate order, latch operating tongues 95 carried by the pistons, by which when one piston is locked its tongue unlocks the opposite piston, and arms pivotally connected to the pistons and to the cylinder in such manner as to effect alternating step by step 100 rotations of said pistons.
7. In a rotary gas engine, a stationary shaft having inlet and exhaust ports; a cylinder rotatably mounted on the shaft, having opposite partitions; rotatable hubs communicating with the inlet and exhaust ports, and opposite pipes extending from each hub and connected with the interior of the cylinder adjacent to the said partitions; automatically operating valves in said pipes; rotatable pistons in the cylinder; arms connected to the pistons and to the cylinder in such manner that the pistons are thereby moved more rapidly than the cylinder; means for locking the pistons to the shaft at 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 - regular intervals, and in alternate order; latch operating devices carried by the pistons whereby when one piston comes to a locked position it unlocks the other piston; 5 spark plugs extending into the cylinder in advance of the pistons; and means connected with the cylinder and with a source of electric power for closing a circuit through said plugs in alternate order and at 10 predetermined periods.
8. In a rotary gas engine as specified, a stationary shaft, having inlet and exhaust ports; a cylinder rotatably mounted thereon, having oppositely arranged partitions; 15 rotatable inlet and exhaust members connected with said ports and with the cylinder; spring-controlled vacuum operated valves in said inlet members; spring-controlled valves in said exhaust members having 20 projecting headed stems; a ring supported concentric with the path of said headed stems, having cam projections at predetermined points for engaging said headed stems, to open said exhaust valves; 25 rotatable pistons in the cylinder; latches in the pistons for automatically locking them to the shaft at regular intervals and in alternate order; means carried by the pistons whereby when one of them comes to a locked 30 position the other is unlocked; arms connected to the pistons and to the cylinder by which the pistons are moved from one locked position to another at a greater rate of speed than that traveled continuously by 35 the cylinder, whereby when each piston comes to a locked position it has confined a body of explosive mixture between itself and a partition; spark plugs extending into the cylinder; and means connected with the cylinder and with a source of electric power for closing a circuit through the said plugs alternately as the adjacent piston is locked.
9. In a rotary gas engine, the combination with a stationary shaft, having inlet and 45 exhaust ports; a rotatable cylinder mounted thereon, having oppositely arranged partitions; rotatable inlet and exhaust members connecting said ports and said cylinder; spring-controlled vacuum operated valves in the inlet members; spring-controlled valves in the exhaust members, having extended 50 stems and cams in the path of said stems for operating the valves; of rotatable pistons in the cylinder comprising radial members and 55 segmental members adapted to rest upon the shaft; stops at equidistant points around the shafts; latches carried by the pistons for successively engaging the stops in alternate order; arms pivotally connected to the pistons and to the cylinder, which move the 60 pistons in alternate order from one locked position to another; tongues extending from the pistons by which one piston is unlocked simultaneously with the locking of 65 the other piston, each of said pistons when
- locked being adapted to confine a body of explosive mixture between itself and an adjoining partition; spark plugs extending into the cylinder adjacent to the partitions; circular conductors secured adjacent to and 70 concentric with the cylinder; opposite contact rollers carried by the cylinder but insulated therefrom, for engaging said conductors, and wires connecting said rollers and the spark plug; a timer ring concentric 75 with the cylinder having two sets of equidistant contacts and independent conductors connecting the contacts; opposite rollers carried by the cylinder and adapted to engage said contacts, said rollers being adapted to convey current from the timer to the cylinder; and wires connecting said timer and conductor rings with a source of power.
10. In a rotary gas engine, the combination with a stationary shaft, having an inlet port at one end and an exhaust port at the opposite end, and a cylinder rotatably mounted thereon, of means for admitting explosive mixture to the cylinder, comprising a rotatable member mounted on the 80 shaft and communicating with the said inlet port and with the cylinder and spring-controlled vacuum operated valves in said member; means for exhausting the exploded gases from the cylinder comprising a rotatable member mounted on the shaft and communicating with the said exhaust port and with the cylinder; spring-controlled valves in said exhaust member having projecting 85 stems, and a stationary ring concentric with respect to the cylinder, having projecting 90 cams at equidistant points adapted to engage the said stems.
11. In a rotary gas engine, the combination with a stationary shaft, having an inlet port at one end and an exhaust port at the opposite end, a cylinder rotatably mounted on the shaft, having oppositely arranged partitions; rotatable inlet and rotatable exhaust members connecting said inlet and exhaust ports respectively, with the cylinder; and automatically operating valves in said members; of rotatable pistons in the cylinder, comprising radial and segmental portions, the latter engaging the shaft; stops at 100 three equidistant points around the shaft; spring operated latches in the pistons adapted to engage the stops; projecting tongues on the segmental portions of the pistons, each of which when its piston is locked is adapted to unlock the other piston, the segmental portions of said pistons being adapted to extend through axial apertures in the cylinder heads; an arm pivoted to the cylinder; a pair of arms pivoted at one end to the first arm and at their opposite ends to the said segmental portions of the pistons, whereby as the cylinder rotates, the pistons are also rotated in alternate step-by-step 110 order.
- 125
- 130

12. In a rotary engine as specified, the combination with a stationary shaft having a central collar provided with an annular groove, and a cylinder rotatably mounted on the shaft, having oppositely disposed partitions; of radial pistons in the cylinder having segmental portions adapted to ride upon said collar and project through the heads of the cylinder, and tongues which ride in the said groove, the said collar being provided with equidistant stop notches; spring actuated latches in the pistons adapted to engage the said notches successively and in alternate order, the tongue of each locked piston being adapted to lift the latch of and release the other piston; an arm pivoted to the cylinder; a pair of arms pivoted to the said arm and to the pistons; means for admitting explosive mixture to and for exhausting exploded gases from the cylinder; and a sparking device operable through the rotation of the cylinder.

13. In a rotary gas engine, a stationary shaft having inlet and exhaust ports in its ends; a cylinder mounted on the shaft having opposite partitions; radial pistons in the cylinder having segmental portions which partially surround the shaft and pass under the inner ends of the partitions; stops at equidistant points around the shaft; latches in the pistons for engaging the stops; valved members connecting the inlet and exhaust port with the cylinder; tongues extending from the pistons for unlatching one of them when the other is locked; arms pivoted to the cylinder and to the pistons, by which the

pistons are alternately rotated step-by-step at a greater speed than that traveled by the cylinder, whereby a body of explosive mixture is confined between the pistons and the adjacent cylinder partition; spark plugs extending into the cylinder adjacent to the partitions; and a sparking mechanism connected therewith, and operable by the rotation of the cylinder.

14. In a rotary gas engine as specified, the combination with a stationary shaft, a cylinder rotatably mounted thereon having rotatable pistons; arms connected therewith and with the cylinder for rotating said pistons; and spark plugs extending into said cylinder; of rollers carried by the cylinder and insulated therefrom; wires connecting the rollers and spark plugs; rollers carried by the cylinder and not insulated therefrom; a stationary ring concentric with the cylinder and comprising inner and outer conductor rings separated by a non-conducting ring, the first mentioned rollers being adapted to engage these rings; a timer ring having equidistant pairs of contacts, which are adapted to be engaged by the second mentioned rollers; and wires connecting said conductor rings and said timer contacts in circuit with a source of electric power.

In testimony whereof I affix my signature in presence of two witnesses.

OLOF F. EDQVIST.
